UNITED STATES PATENT OFFICE.

EVELD L. NELSON, OF MINNEAPOLIS, MINNESOTA.

DESIGN FOR A MIRROR-PEDESTAL.

52,169.

Specification for Design.

Patented July 9, 1918.

Application filed April 18, 1918. Serial No. 229,453. Term of patent 14 years.

To all whom it may concern:

Be it known that I, EVELD L. NELSON, a citizen of the United States, residing at Minneapolis, county of Hennepin, and State of Minnesota, have invented a new, original, and ornamental Design for a Mirror-Pedestal, of which the following is a specification, reference being had to the accompanying drawing, in which—

The figure is a perspective view of a mirror pedestal constructed in accordance with the invention.

I claim:—

The ornamental design for a mirror pedestal, as shown.

EVELD L. NELSON.

Witnesses:

FRED N. ATWOOD,
WILBER B. CLARK.
